OSCILLATOR

Merl T. Reynolds, Ballston Lake, N. Y., assignor
to General Electric Company, a corporation of
New York

Application November 12, 1947, Serial No. 785,261

9 Claims. (Cl. 250—36)

1

This invention relates to electronic circuits obtaining negative transconductance and to electron discharge device oscillator circuits employing the phenomenon of negative transconductance.

A general object of the invention is to provide improved electron discharge device circuits obtaining negative transconductance.

An object of the invention also is to provide an improved negative transconductance oscillator.

A more specific object is to provide an oscillator of the negative transconductance type wherein the frequency determining tuned circuit has one terminal at ground potential.

A further object is the provision of an oscillator comprising a small number of components which will provide stable sine-wave signals with low distortion over a wide range of frequencies.

An additional object is to provide an oscillator from which an output voltage of high intensity is obtainable without direct connection to the frequency determining elements.

It is also an object of the invention to provide an oscillator which will become inoperative to generate oscillations upon disconnection of the inductance included in the tuned circuit.

Another object is to provide a negative transconductance oscillator in which the tuned circuit inductance has no tapped connection.

It is a further specific object of my invention to provide an improved negative transconductance oscillator operable over a wide band of frequencies, wherein one terminal of the parallel tuned circuit is maintained at direct current ground potential, wherein the other terminal is connected to the third, or screened, grid rather than to the first grid, the first grid being directly grounded, and wherein operation up to very high radio frequencies is practicable without the necessity of providing tuned filter circuits to isolate the screen grid from the low impedance power supply.

The novel features which I believe to be characteristic of my invention are set forth with particularity in the appended claims. My invention itself, however, both as to its organization and method of operation, together with further objects and advantages thereof may best be understood by reference to the following description taken in connection with the accompanying drawing in which Fig. 1 is a circuit diagram of an oscillator in accordance with my invention; Fig. 2 is a circuit diagram of an oscillator similar to that of Fig. 1 but incorporating additional

2

components and possessing additional advantages; and Fig. 3 is a group of curves explanatory of the operation of oscillators according to the invention.

Referring now to Fig. 1, I have shown a pentagrid discharge device 1 comprising a grounded cathode 2, a first grid 3, which is also grounded, a screen grid consisting of grid elements 4 and 5 disposed on opposite sides of a second control grid 6, being the third grid from the cathode, which may be referred to as the screened grid. Grounded suppressor grid 7, the fifth grid from the cathode, is arranged inside anode 8, the anode being directly connected to a source of positive B+ potential, such as the battery 9, the negative terminal of the source being grounded. The impedance of the potential source is made low for the frequencies at which operation is desired by connecting a capacitor 10 of high capacity from B+ to ground.

A frequency determining parallel-tuned circuit comprising inductance 11 and condenser 12 is connected between control grid 6 and ground, and a feedback circuit including a series condenser 13 is arranged to feed back oscillatory energy from the screen grid 4 and 5 to the tuned circuit. As explained below the feedback through condenser 13 is in phase with the voltage appearing on control grid 6. If the value of condenser 13 is made low, the oscillator output will very closely approach a true sine wave. Higher values, however, may be desirable to insure strong oscillation over a wider range of supply voltage variations or over a wider range of frequencies. B+ supply for the screen grid is through a load resistor 14, across which the output signal is developed.

A modification of the device is shown in Fig. 2 wherein the output signal is derived from a load resistor in the anode circuit of the oscillator.

In this modification, the cathode 2 of device 1 is connected to ground through self-biasing network 15. The first and fifth grids, 3 and 7, respectively, are both connected directly to ground, the second grid 4 and fourth grid 5, comprising the screen grid, are connected to the B+ potential source, battery 9, through a load resistor 14, and the tuned circuit comprising inductance 11 and parallel capacitor 12 has one terminal grounded and the other connected through capacitor 13 to feed back energy to the screened grid 6.

The anode circuit in the device of Fig. 2 contains a load resistor 16 across which the oscillating output voltage is developed. The resistor

may conveniently be arranged as a potentiometer, as shown, in order that the output voltage derived from the movable contact may be adjusted in intensity. A direct current blocking capacitor 17 may be connected in series with the output terminal in a known manner, if desired.

The operation of the oscillators of Fig. 1 and Fig. 2 may be best explained with reference to Fig. 3. As shown by the curves of Fig. 3, which are labeled to indicate current (I) or voltage (E) for the elements of tube 1, an increase in the potential of the third grid 6, along the abscissa of the chart, produces a decrease in the current, curve I_{4,5}, to the interconnected second and fourth grids 4 and 5, and a resultant increase in the potential thereon, curve E_{4,5}, because of the lower current through resistor 14, if the discharge device 1 is biased to operate at approximately the operating point indicated on the chart by a vertical dashed line. The increase in potential of grids 4 and 5 occurs simultaneously with the increase in potential of the third or screened grid 6 and provides an energy feedback to grid 6 through capacitor 13. The energy thus fed back is sufficient to overcome the circuit losses, and oscillations thus occur which are at the resonant frequency of the tank circuit 11, 12. It will be understood that the resonant frequency will be affected by the inherent capacitance of the circuit elements, which is effectively in parallel with capacitor 12, as well as to a small extent by the inherent inductance of the circuit.

The anode 8 of the discharge device in Fig. 2 is provided with a load resistor 16 connected in series to the source 9 of positive operating potential. The resistor may conveniently comprise a potentiometer resistance provided with a variable tap as shown to select a desired value of output voltage for furnishing to external apparatus through capacitor 17. The device of Fig. 2 exhibits an anode voltage curve such as E₈ in Fig. 3, whereas, of course, the anode voltage of the device of Fig. 1 is constant and would appear on the chart as a horizontal straight line.

An oscillator according to either of Figs. 1 or 2 of the drawings has wide frequency range and stability characteristics which particularly adapt them to use in devices for determining the inductance or capacitance of elements which may be inserted in the tuned circuit 11, 12.

For instance, if the value of the inductance of element 11 is unknown, but the capacitance of condenser 12 is available from a calibrated dial or otherwise, the condenser 12 may be adjusted until the frequency of the oscillator coincides with that of an external standard oscillator. The resonant frequency of the tuned circuit 11, 12 and the value of the capacitance 12 being both known, the inductance of element 11 is readily calculated.

For such use of the oscillator, it will be obviously desirable that taps on the inductance in the tuned circuit should be unnecessary, that one end of the inductance should be grounded for both direct currents and alternating currents, that the oscillator should be inoperative if there is no inductance element in the circuit, that there should be no substantial change under varying output load conditions, that the oscillator should be stable, relatively unaffected by supply voltage variations, and that it should provide oscillations over a very wide band of frequencies.

The oscillator according to this invention successfully meets all of these criteria, is simple in construction, is composed of ordinary commer-

cially available components, and the values of the components are not critical, except, of course, that for accurate results, it may be necessary to provide accurate calibration of the values of inductance 11 or capacitor 12 if the value of one of these two elements is known and is to be determined as outlined above.

While I have shown only certain preferred embodiments of my invention by way of illustration, many modifications will occur to those skilled in the art and I therefore wish to have it understood that I intend, in the appended claims, to cover all such modifications as fall within the true spirit and scope of my invention.

15 What I claim as new and desire to secure by Letters Patent of the United States is:

1. An electron discharge device oscillator system obtaining negative transconductance, comprising a vacuum tube having therein a cathode, 20 a first grid, a screened grid, a screen grid and an anode, a screen grid-to-cathode circuit comprising a source of direct current operating potential, a load resistor extending from said screen grid to a first point in said circuit which is positive 25 with respect to said cathode, a parallel tuned tank circuit connected between said screened grid and a second point in said circuit which is negative with respect to said first point, a feedback coupling from said screen grid to said 30 screened grid, a connection for said first grid to said circuit for maintaining said first grid at a potential negative with respect to said first point, and means for energizing said anode.

2. An oscillator comprising a tuned circuit 35 with two terminals, an electron discharge device with an anode, a cathode, a control grid and an anode grid, said anode grid comprising two sections respectively disposed on opposite sides of said control grid, said grids being disposed between said anode and said cathode, means for establishing a potential gradient between said anode and said cathode such that an increase in control grid potential causes an increase in anode 40 grid potential, and means to feed back to said control grid without substantial phase shift changes in said anode grid potential, said tuned circuit being connected in a control-grid-to cathode circuit.

3. In an oscillator with two output terminals 50 and including a resonant circuit, an electron discharge device with an anode, a cathode and five grids between said cathode and anode, the first and fifth of said grids from said cathode being connected to a point at ground potential, one of 55 said terminals being connected to said ground point, the other of said terminals being connected to the second and fourth of said grids, said interconnected second and fourth grids being connected through a load impedance to a source of 60 positive potential, regenerative feedback coupling from said second and fourth grids to the third of said grids, means for providing operating potentials to said cathode and said anode, and means for biasing said third grid to a potential relatively negative with respect to said 65 interconnected second and fourth grids.

4. An oscillator comprising a tuned circuit, an electron discharge device with an anode, a cathode, a control grid and an anode grid, said anode 70 grid comprising two sections respectively disposed on opposite sides of said control grid, said grids being disposed between said anode and said cathode, means for establishing a potential gradient between said anode and said cathode such that an increase in control grid potential causes 75

an increase in anode grid potential, means to feed back to said control grid without substantial phase shift changes in said anode grid potential, said tuned circuit being connected in a control-grid-to-cathode circuit, and output means associated with said anode.

5. In a negative transconductance oscillator including a resonant circuit, an electron discharge device with an anode, a cathode and at least four grids between said cathode and anode, means for supplying a relatively large positive operating potential to said anode with respect to the potential of said cathode, means maintaining not more than relatively small respective biasing potentials from the second and fourth grids to said cathode, said last means comprising said resonant circuit in series with said second grid, means interconnecting and maintaining the first and third grids at a more positive potential than any of the other grids in said device and less positive than said anode, an inphase feedback circuit from said interconnected first and third grids to said second grid to sustain oscillation in said resonant circuit.

6. An electronic oscillator comprising an electron discharge device with an anode, a cathode, a control electrode, a screen electrode in two connected portions arranged respectively on opposite sides of said control electrode to screen said control electrode toward said anode and toward said cathode, and a grid adjacent said anode, said anode being connected to a point in a source of potential positive with respect to said cathode, means comprising a series impedance connecting said screen electrode to a point of said source of potential not more positive than the point of connection for said anode, said grid being maintained at a potential negative with respect to the potential of said screen electrode to form with said anode a virtual cathode for said screen electrode, means comprising another impedance for biasing said control electrode negative with respect to said screen electrode, means forming a resonant circuit with one of said impedances, and means for feeding back in-phase energy from said screen electrode to said control electrode.

7. An electronic circuit obtaining negative transconductance comprising an electron discharge device with an anode, a cathode and five grids, said grids being arranged in sequence from said cathode to said anode, means maintaining the first and fifth of said grids substantially at a fixed reference potential, means providing a positive operating potential to said anode, means maintaining said cathode at a potential less positive than the cut-off potential established by the

potential of said first grid, means for providing a positive operating potential to the second and fourth of said grids together through a load impedance, means for biasing the third of said grids to a potential substantially the same as that of said first grid and for applying a signal to said third grid whereby said signal produces a corresponding in-phase signal across said load impedance.

8. A circuit obtaining negative transconductance comprising an electron discharge device with an anode, a cathode, and five grids in sequence between said cathode and said anode, means providing positive operating potentials to said anode and through an impedance to the second and fourth of said grids, said second and fourth grids being interconnected, means for biasing the first grid with respect to said cathode to a potential within the operating range of said device, means for biasing the third and fifth grids to substantially the potential of said first grid, and means to provide a signal to said third grid whereby a corresponding signal in phase with the signal on said third grid appears on said second and fourth grids.

9. A negative resistance comprising an electron discharge device with an anode, a cathode and at least four grids, means providing a positive operating potential to said anode with respect to said cathode, two of said grids comprising a screen grid, another of said grids comprising a control grid and being disposed between said last mentioned two grids thereby to be screened from said anode and from said cathode, the fourth of said grids being disposed between said screen grid and said anode, means comprising an impedance in series with said screen grid providing an operating potential to said screen grid not more positive than said anode potential, means for biasing said fourth grid negative with respect to said screen grid, means for biasing said control grid negative with respect to said screen grid, and a capacitor connected to feed back in-phase energy from said screen grid to said control grid.
